UNITED STATES PATENT OFFICE.

WILLIAM R. SMITH, OF BOSTON, MASSACHUSETTS, ASSIGNOR OF ONE-HALF
TO F. A. HOUDLETTE, OF BOSTON, MASSACHUSETTS.

PIPE-BENDING MACHINE.

SPECIFICATION forming part of Letters Patent No. 735,307, dated August 4, 1903.

Application filed October 23, 1902. Serial No. 128,467. (No model.)

To all whom it may concern:

Be it known that I, WILLIAM R. SMITH, of Boston, in the county of Suffolk and State of Massachusetts, have invented certain new and useful Improvements in Pipe-Bending Machines, of which the following is a specification.

This invention relates to appliances or machines for bending pipes, and has particular reference to that type of such devices which are employed for bending short lengths of pipe.

While the invention in the embodiment shown in the drawings is adapted particularly for hand use, so that it might be termed a "tool" or "appliance," yet it is capable, as will be readily understood hereinafter, of being embodied in a machine so that the moving parts may be driven by power.

One object of the invention is to provide an improved construction of bending-rolls having grooved peripheries which at the meeting-point of the two rolls will present in cross-section an elliptical passage as distinguished from a true circle.

Another object of the invention is to provide a construction of roll which will enable an adjustment of the width thereof to be made.

A further object is to provide means for holding the pipe, which means may also constitute a passage for the supply of steam or other fluid or material for filling the pipe and warming it and for resisting compressive pressure during the bending operation.

To these ends the invention consists in the construction and arrangement of parts, substantially as hereinafter described and claimed.

Of the accompanying drawings, Figure 1 represents a side elevation, partly in section, representing the invention in one of the forms in which it may be embodied. Fig. 2 represents a front view of the same. Fig. 3 represents an enlarged diametrical section of one of the rolls and an edge elevation of the other. Fig. 4 represents an enlarged section taken through the pipe-holder and nipple and connections. Fig. 5 represents a modification hereinafter described.

The same reference characters indicate the same parts in all the figures.

In the embodiment of the invention illustrated in the drawings a suitable standard, upright, or beam is represented at *a*, to which is secured a plate *b*, having bracket-arms *b'*, supporting the pivot *c'* of a lever *c*. Said lever *c* carries the upper bending-roll *d*, and a lower bending-roll *d'* is mounted on the pivot *c'* of the lever.

A pipe *e* extends through the plate *b* and standard *a* in alinement with the opening between the two rolls when the lever *c* is in upright position. Behind the upright *a* said pipe *e* is connected to a pipe *f* by means of a coupling *e'*. Said pipe *f* is to be connected to a suitable source of steam or of other fluid or material adapted to be forced into the pipe to be bent, as hereinafter described. The front end of the pipe *e* is formed externally with a screw-thread, which is preferably a left-hand thread, and fitted thereto is a sleeve *g*, which is internally threaded at its inner end to fit the threads of the projecting portion of the pipe *e*, and which sleeve is at its outer end formed with an internal thread to fit the usual right-hand thread formed on the end of the pipe to be bent. The sleeve *g*, carried by the pipe *e*, constitutes a socket for the pipe to be bent and at the same time constitutes a nipple through which the hot fluid or other material referred to may be forced into said pipe. If no steam or other fluid or equivalent thereof is to be forced into the pipe to be bent, the parts *e* and *g* may be a simple socket.

In the use of this device a pipe *x* is inserted between the rolls in the position indicated by full lines in Fig. 1, the outer end of said pipe being provided with a cap *x'*. Said pipe is screwed into the socket of the sleeve *g*, and then the heating medium is introduced through the pipe *e*, if such medium is to be employed, the pipe *x'* serving to prevent the escape of such medium. The lever *c* is then turned toward the position represented by the dotted lines in Fig. 1, causing the roll *d* to bend the pipe *x* over the periphery of the roll *d'*. This operation of bending is well known, with the exception of the heating medium. By the employment of the heating

medium I am able to facilitate the bending of the pipe, and also, if such medium is under sufficient pressure, an internal support is afforded for the pipe while being bent. It

5 will thus be seen that the pipe *e* and sleeve *g* constitute a combined pipe-holder and supply-nipple.

As clearly shown in Fig. 3, the grooves of the rolls are not semicircular in cross-section.

10 Instead they are semi-elliptical, so that the opening between the contacting portions of the two rolls will form a true ellipse. This prevents the flattening of the pipe during the bending operation. I have found in practice that when two rolls are employed having grooves of such shape that the passage between the contacting points of the rolls is a true circle the operation of bending the pipe results in flattening it. This is due to 15 the fact that the outer side of the pipe is stretched, while the inner side is contracted. The pipe will retain a diameter equal to the width of the passage-way in a plane parallel with the axis of the rolls, but will be flattened in a direction at a right angle to the axes of the rolls. By giving a semi-elliptical form to the grooves I prevent an undue compressing action upon the outer surface of the curve of the pipe as it is being bent, 20 while the width of the opening between the two rolls is designed to be such that the said opening will closely receive the pipe. In other words, the external diameter of the pipe to be bent should be practically the same 25 or but very slightly smaller than the shortest diameter of the opening or passage between the rolls.

In order to provide an adjustment whereby the width of the grooves in the rolls may 30 be varied, I make said rolls in two parts, as clearly shown in Figs. 3 and 5. As shown in Fig. 3, I interpose between these parts spacing-disks or circular plates *h*, which may be, as here shown, perfectly flat. By varying the 35 thickness of the interposed spacing-plates I vary the width of the groove. In Fig. 5 I show a spacing disk or plate *h'* which is

fluted, so that it will yield to some extent upon screwing up the bolts which connect the two halves of the roll.

50

I claim—

1. A pipe-bending machine comprising contacting rolls, one of which is movable about the axis of the other, said rolls having semi-elliptical grooves in their peripheries, adapted to conjointly form an elliptical passage for pipe to be bent, each of said rolls comprising two parts bolted together and adapted to receive spacing-plates between them. 55

2. A pipe-bending machine comprising a pair of rolls, one of which is movable about the axis of the other, the said rolls comprising two parts bolted together and adapted to receive spacing-plates between them. 60

3. A pipe-bending machine comprising a lever having a grooved roll, another grooved roll having its axis coincident with the pivot of the lever, and a combined pipe-holder and supply-nipple in alignment with the opening between the two rolls when the lever is in inoperative position, said pipe-holder and supply-nipple being connected with a rigid support. 65

4. A pipe-bending machine comprising a plate having a bracket, a suitable support for said plate, a grooved roll mounted in said bracket, a lever mounted to vibrate on a pivot coincident with the axis of said roll, a grooved roll carried by said lever and mounted to have peripheral contact with the first-mentioned roll, a pipe extending through said plate in alignment with the opening between the two rolls when the lever is in inoperative position, and a sleeve carried by said pipe and having an internally-threaded portion adapted to receive the threaded end of a pipe 85 to be bent.

In testimony whereof I have affixed my signature in presence of two witnesses.

WILLIAM R. SMITH.
